UNITED STATES PATENT OFFICE

EUGENE D. NICHOLS, OF FORTUNA, MISSOURI

BALING PRESS

Application filed July 22, 1930. Serial No. 469,743.

This invention relates to presses for baling hay, and a primary object of this invention is to provide a baling press equipped with an improved plunger, and further to provide a baling press of the above mentioned character which consists of but relatively few parts, thus rendering the baler less likely to become out of order, easily repaired, and otherwise more efficient over the present type 10 of baler.

With the above and numerous other objects in view, the invention consists in the novel combination and arrangement of parts and details of structure hereinafter more fully described and claimed, reference being had to the accompanying drawings, wherein:

Figure 1 is a longitudinal vertical section of a portion of a baling press having my invention applied thereto,

20 Figure 2 is a side elevational view of the improved plunger,

Figure 3 is a detail view partly in section and partly in elevation showing the lid or apron of the plunger head in a raised position, the sections taken substantially on the line 3—3 of Figure 4,

Figure 4 is a top plan view of the plunger, certain parts being shown broken away,

25 Figure 5 is a transverse sectional view taken substantially on the line 5—5 of Figure 4.

With reference more in detail to the drawings, it will be seen that the frame 1 of the press is of the customary construction as shown, and 2 indicates the usual hopper, the presser foot is designated by the reference character 3, and the said presser foot at its upper end is pivotally connected to a link 4 and in turn is pivotally connected to the 35 upper end of the standard 5 mounted on the frame 1.

A lever 6 is pivoted intermediate its ends on the upper end of the standard 5 as at 7, and the curved forward end of the lever 6 is 40 pivoted to the presser foot 3 adjacent the upper end of the presser foot, the presser foot 3 being of course adapted to force baling material from the hopper into the baling 45 chamber, and the upper end of the hopper is

notched as at 8 for accommodating link 4 and lever 6.

The bull wheel of the press is designated generally by the reference character 9. My improved plunger comprises an elongated 55 skeleton frame F that is substantially rectangular in cross section. The frame F at its forward and rear ends are supported on suitable wheels or casters 10. The plunger F is adapted to travel longitudinally upon the 60 bottom of the baling press into and out of the baling chamber designated by the reference character C.

Mounted in the forward end of the frame F is a head member 11. The head member 11 65 at opposite sides thereof is suitably notched as at 12 for accommodating dogs 13 arranged on the side walls of the chamber C when the plunger is moved inwardly of the chamber.

Figure 2 is a side elevational view of the improved plunger,

70 A pitman 14 is pivoted at its forward end to the rear face of the head member 11 as at 16, and the rear end of the pitman 14 is pivotally connected to the bull wheel 9 through the medium of an eccentric pin 16. The bull wheel 9 is operated through the 75 medium of suitable gearing such as is employed for such purposes, and obviously, during rotation of the bull wheel 9, reciprocal movement will be imparted to the plunger for moving the same into and out of the chamber C.

80 A link 17 is pivotally connected at one end to a lug 18 formed on the pitman 14 adjacent the forward end of the pitman. The opposite end of the link 17 is pivotally connected to the rear end of the lever 6 as at 19 and through the medium of the link connection 17, it will be seen that the plunger and presser foot 3 are operatively connected so as to operate simultaneously with one another but in suitable timed relationship as to insure there being no chance of conflict between the plunger and the presser foot.

85 Secured to the side members of the frame F at the forward end of the latter is a plate 20 that extends transversely of the plunger. To the inner edge of the plate 20 there is hinged as at 21 an apron or cover plate 22. A headed stud 23 projects upwardly from the link 17 and extends through a suitable 100

opening 24 provided therefor in the apron 22 adjacent the free end of the apron.

The purpose of the apron 22 is to prevent hay from falling into the frame F when the latter is moved inwardly of the chamber C. In this connection then it will be seen that the movement of the apron 22 about its hinge 21 will be controlled by the operation of the link 17, with the result that as the plunger moves inwardly of the chamber C resulting in the raising of the presser foot 3 and in the positioning of the link 17 in the position shown in Figure 2, the apron 22 will rest flat upon the top of the frame F or in a closing position, at which time the plunger will be within the chamber C. As the plunger begins its withdrawal stroke, the apron 22 will be gradually raised upwardly or swung about its hinge 21 under action of the link 17 until the apron 22 assumes that position suggested in Figure 1, at which time the plunger will be at the end of its return stroke.

Even though I have herein shown and described the preferred embodiment of my invention, it is to be understood that the same is susceptible to changes fully comprehended by the spirit of the invention as herein described, and the scope of the appended claims.

Having thus described my invention, what I claim as new is:

1. A baling press including in combination, a presser foot, a pivotally mounted lever therefor, a bull wheel, a plunger, a pitman pivotally connected at one end with the plunger and at its other end eccentrically connected with the bull wheel, a link pivotally connected to the pitman adjacent the first mentioned end of the pitman at one end of said link, the other end of said link being pivotally connected to said presser foot lever, an apron hingedly mounted adjacent one end thereof to the plunger, said apron at its free end adapted to engage the link, and said link intermediate its ends provided with a headed stud extending through an opening provided in the free end of said apron whereby to provide a loose connection between said apron and said link.

2. A baling press including in combination, a lever actuated presser foot, a pitman actuated plunger, an apron pivotally mounted on the plunger, a link pivotally connecting the presser foot lever with the pitman actuating the plunger, and a stud projecting from the link and extending through an aperture provided in the apron remote from the pivot of the apron.

60 In testimony whereof I affix my signature.
EUGENE D. NICHOLS.
